Specification of Letters Patent.

Patented Apr. 19, 1921.

Application filed August 4, 1919. Serial No. 315,116.

To all whom it may concern:

Be it known that I, ALBERT E. HUDSON, a citizen of the United States, residing at Beverly, in the county of Essex and State 5 of Massachusetts, have invented certain Improvements in Presses, of which the following description, in connection with the accompanying drawings, is a specification, like reference characters on the drawings indicating like parts in the several figures.

This invention relates to presses and is herein set forth for the purpose of illustration, but not by way of limitation, with particular reference to its use in the cutting of 15 sheet material by freely movable dies.

One of the machines commonly employed in the cutting of heavy leather stock and of substantial piles of layers of fabric is a press, known to the trade as the beam dinker, and comprises characteristically a work supporting block or cutting bed and a beam or crosshead presser member carried by four rods arranged vertically in pairs at the end of the presser member by which the 20 latter is reciprocated in pressure applying operations toward and from the cutting bed. This machine is widely used because of its certainty in operation, the construction by which the presser member or beam is acted 25 upon at both of its ends insuring that the cutters or dies will be forced completely through the work at each reciprocation of the beam. It has, however, a disadvantage that limits its usefulness greatly. Since the 30 beam, in its upper position of rest, is closely adjacent to and directly over the cutting bed, it is impossible because of the limited space and the restricted amount of light to determine the proper location of the die on the work. Hence with this machine it is 35 not possible to obtain even a close approximation of the maximum value in blanks from the material subjected to cutting operations. Consequently, it has been proposed to modify the construction of the machine in such a manner as to uncover the work supporting bed while the machine is at rest so as to afford opportunity for careful 40 inspection of the work on the bed, and especially of leather stock, as a preliminary to the positioning of the die, and to permit of proper manipulation of the work and of the die in locating it on the work. Of the constructions heretofore proposed none has 45 proved entirely satisfactory.

It is an object of the present invention to provide an improved press of the class described in which the presser member or beam may be moved relatively to the work supporting bed so as to uncover the latter to 60 any extent desired by the operator.

In the illustrative embodiment of the invention the upper ends of the vertically reciprocable rods at each end of the beam or presser member are joined together by cross-bars which provide guideways in which the 65 ends of the presser member are received for sliding movements of the presser member from front to rear of the machine and in the reverse direction, the said crossbars providing also the connecting means between the 70 vertical rods and the ends of the presser member or beam through which power is transmitted in applying the oftentimes immense pressure of the presser member or 75 beam upon the work. If the vertical rods at one end of the machine be alined from front to rear as in the well-known constructions, they will both be located at one side of the guideway in the crossbar, thus providing 80 an organization of considerable inherent weakness. Hence it is a further object of the invention to provide operating means for the presser member which, while constructed to permit of lateral movement of 85 the presser member relative to the work supporting bed, will combine great strength with simplicity of construction.

In one important aspect, therefore, the invention contemplates the provision, in a machine of the class described in which a presser member or beam is laterally movable with respect to the work supporting bed, of operating means so arranged that the presser member may be moved laterally 90 relatively thereto and so constructed, without undue weight of material, as to insure the application of the requisite pressure by the presser member in pressure applying operations.

In operating with the illustrative machine the presser member will be brought forward completely over the bed when a large die is to be driven through the work or when the die is located adjacent to the front edge of 105 the cutting bed. The construction is such, however, that the presser member may, with complete safety, be moved from its rear position forwardly a distance just sufficient to cover a die at the rear of the cutting bed 110

and operated to force the die through the work. By this arrangement considerable time and effort will be saved, since a good proportion of the operations do not require 5 that the presser member be in extreme forward position.

In another aspect the invention resides in an improved press wherein the presser member may occupy various positions relative to 10 the work supporting bed to coöperate with the whole bed or with selected portions thereof at the will of the operator.

Other objects and features of the invention will be apparent from the following 15 detailed description and will be pointed out in the claims.

In the drawings:—

Figure 1 is a perspective view partly in section of a press illustrating one embodiment of the invention, and

Fig. 2 is a detail view showing a plan of one end of the press and illustrating the arrangement of the vertically reciprocable posts.

In the illustrative machine there is provided the usual work supporting bed 4, supported upon a portion of the frame 6, the latter having, preferably, bearings, one of which is shown at 8, for vertically reciprocable posts 10 one at each corner of the work supporting bed. Means are provided for connecting the posts in pairs at each end of the bed, said connecting means comprising preferably cross bars 12 which are slotted in the illustrative construction as at 14 to provide guideways adapted to receive the ends of the presser member 16. The arrangement is preferably such that the presser member may be moved laterally to 40 uncover the work supporting bed, means being provided in the form of rollers 18 mounted in the ends of the presser member to sustain the presser member in the guideways of the crossbars 12 and of the extensions 13 thereof and to lessen friction during the lateral movement of the presser member. In order that the operative may readily shift the presser member into position over the bed or into a position in the 45 rear portion of the guideways so as completely to uncover the bed, handles 20 are provided on the front edge of the presser member to be grasped by the operator in moving the presser member. It will be noted that the crossbars 12 in connection with the vertical rods or posts 10 constitute the operating means for the presser member, connections being provided between the lower ends of the posts and the main shaft 50 of the machine as in the well-known beam dinker construction. An important feature of the construction of the crossbars 12 is that which relates to the relative position of the crossbars and especially the upper plate 55 portion 15 thereof with respect to the verti-

cal posts or rods. In the illustrated construction the posts at the front of the cutting bed are nearer together than the two posts at the rear of the cutting bed, the former being spaced a distance considerably

less than the length of the presser member,

while the two posts at the rear of the cutting bed are spaced apart a distance greater

than the length of the presser member. By

this arrangement the posts at one end of the

presser member are so positioned with re-

spect to the guideway in the connecting

crossbar that they are on opposite sides of

the longitudinal axis of the guideway in the

crossbar and hence the upper plate 15 of

the cross bar lies substantially on a line con-

necting the centers of the upper ends of the

posts and, at the same time, overlies the ad-

jacent end of the presser member. In other

words, the construction is such as to pro-

vide in effect a crossbar extending directly

between the upper ends of the posts and

overlying the end of the presser member.

Obviously this construction is markedly su-

perior to one in which the posts are both on

the outer side of the guideway for, in such

case, the plate which would overlie the end

of the presser member would be wholly to

one side of a line joining the upper ends of

the posts, thus subjecting the latter to un-

usual and dangerous strains tending to bend

or break the posts during the application

of pressure upon the work. As a further

means for strengthening the top plate 15 of

the cross bar there is provided preferably a

ridge or bar of metal integral with the top

plate and indicated in the drawings by ref-

erence character 22.

In operating with the machine the presser member will ordinarily be displaced rear-

wardly so as completely to uncover the work supporting bed 4. With the presser member in rearward position, the work may

be readily placed upon the bed 4 and sub-

jected to the careful inspection that is nec-

essary especially with leather stock. The

die is then positioned according to the best

judgment of the operator and the presser member is drawn forwardly to cover the

die. If the die be one of the largest used

or, if it be positioned adjacent to the front

edge of the bed, the presser member will be

drawn forwardly to its extreme forward

position and the machine tripped, as the

presser member is approaching said posi-

tion, to force the die through the sheet mate-

rial. With the presser member in its ex-

treme forward position, the operating means

is so positioned with respect thereto that the

cross plate 15 comprising also the strength-

ening ridge 22 lies entirely across the end

of the presser member, thus providing a con-

struction capable of applying the necessary

pressure on the work. On the other hand, if

the die to be forced through the work is

130

one of the smaller sizes used and is located toward the rear of the cutting bed, it is not necessary to move the presser member to its extreme forward position since the cross bars 12 with their extensions are of sufficient strength to operate the presser member when the latter is meeting with more moderate resistance as in operating upon small dies. In this connection, it is desired to call attention to the fact that the crossbars 12 and their extensions 13 which provide the guideways for the presser member are solidly constructed as integral, imperforate members, that is, the guideway is closed in 15 solidly on three sides, there being no slot or opening other than that through which the presser member enters. Since a considerable proportion of the dieing out operations will take place at the rear of the cutting bed, it is obvious that no inconsiderable saving in 20 time and effort will be effected by the arrangement shown, wherein the presser member may be moved relatively short distances in covering and uncovering the die. 25 It should be stated, moreover, that the operators soon acquire such skill with the operation of the machine that they trip the machine to cause a pressure applying operation while the presser member is moving 30 toward position over the die.

Having thus described my invention, what I claim as new and desire to secure by Letters Patent of the United States is:

1. In a machine of the class described, a 35 work supporting bed, a presser member movable toward and from said bed and also laterally with respect to the bed, and means for operating the presser member in pressure applying operations comprising vertically reciprocable rods and cross plates connected to said rods and arranged to engage 40 one over each end of the presser member when the latter is in its extreme forward position over the work supporting bed, considerable 45 portions of the plates being arranged to lie on both sides of lines connecting the upper ends of the rods to provide a construction that will insure the application of requisite pressure on the work. 50 2. In a machine of the class described, a work supporting bed, a presser member, means for moving the presser member toward and from the work supporting bed comprising vertically reciprocable rods, and 55 cross bars connecting said rods in pairs at each end of the presser member and each having a plate provided with a reinforced portion arranged to overlie the end of the presser member along both sides of a line 60 connecting the upper ends of the rods.

3. In a machine of the class described, a work supporting bed, a presser member, means to move the presser member toward and from the bed in pressure applying operations comprising reciprocable rods ar-

ranged in pairs at each end of the presser member, crossbars connecting the rods in pairs and each comprising a plate arranged to overlie the adjacent end of the presser member along both sides of a line passing 70 through the plate-engaging ends of the rods.

4. In a machine of the class described, a work supporting bed, a presser member movable toward and from the bed in pressure applying operations, means for operating 75 the presser member comprising vertically reciprocable rods arranged in pairs at each end of the presser member, the arrangement being such that the distance between the two vertical rods at the front of the machine is less than the length of the presser member while the distance between the two rods at the rear of the machine is greater than the length of the presser member, and crossbars connecting said rods in pairs at 80 each end of the presser member and having portions which overlie the ends of the presser member.

5. In a machine of the class described, a work supporting bed, a presser member, 90 means for moving the presser member in pressure applying operations toward and from the work supporting bed comprising vertically reciprocable rods arranged in pairs at opposite ends of the presser member, and crossbars connecting said rods and each provided with a guideway for slidably receiving the adjacent end of the presser member, the construction and arrangement being such that the upper ends of the rods 100 lie on opposite sides of the longitudinal axis of the guideway so that the upper portion of each crossbar provides a cross plate lying on an axis passing through the centers of the rods and overlying the ends of the presser 105 member.

6. In a machine of the class described, a work supporting bed, a presser member, means for operating the presser member in pressure applying movements toward and 110 from the work supporting bed comprising vertically reciprocable rods and crossbars connecting said rods in pairs at the ends of the presser member, each crossbar being provided with a guideway for slidably receiving the end of the presser member, the crossbars throughout their length providing guideways having integral and imperforate 115 walls on three sides.

7. In a machine of the class described, a work supporting bed, a presser member, vertically reciprocable posts arranged in pairs at each end of the presser member, and crossbars connecting the posts in pairs at each end of the presser member and provided with guideways for slidably receiving the adjacent end of the presser member, the presser member being constructed and arranged for coöperation with the bed in pressure applying operations when in 120 125 130

positions intermediate of its extreme forward and rearward limits of movement as well as when in its extreme forward position.

5 8. In a machine of the class described, a work supporting bed, a presser member, vertically reciprocating posts arranged in pairs at opposite ends of the presser member, plates connecting the posts for supporting the respective ends of the presser member, the posts being so arranged that the planes defined by the posts at each end of the presser member converge to a line in front of the machine, and plates connecting the posts and overlying the respective ends of the presser member.

10 9. In a machine of the class described, a

work supporting bed, a presser member, vertically reciprocable posts arranged in pairs at each end of the presser member, 20 crossbars connecting the posts in pairs at each end of the presser member and provided with guideways for slidably receiving the adjacent ends of the presser member, and means for manually moving the 25 presser member in said guideways, the presser member being constructed and arranged to coöperate in pressure applying operations with the whole or any desired portion of said work supporting bed at the 30 will of the operator.

In testimony whereof I have signed my name to this specification.

ALBERT E. HUDSON.
